SHOE OR THE LIKE

Jack Abowitz, New York, N. Y.

Application December 15, 1953, Serial No. 28,076

Term of patent 7 years

(Cl. D7—7)

To all whom it may concern:

Be it known that I, Jack Abowitz, a citizen of the United States of America, residing in New York city, county of New York, and State of New York, have invented a new, original, and ornamental Design for a Shoe or the like, of which the following is a specification, reference being had to the accompanying drawing, forming part thereof.

The figure on the drawing is a front perspective view of a shoe or the like, showing my new design. The opposite side is substantially the same as that shown on the drawing.

I claim:

The ornamental design for a shoe or the like, substantially as shown and described.
